UNITED STATES PATENT OFFICE.

ROBERT S. WEST, OF CLEVELAND, OHIO.

DISINFECTING APPARATUS.

SPECIFICATION forming part of Letters Patent No. 634,490, dated October 10, 1899.

Application filed March 2, 1899. Serial No. 707,434. (No model.)

To all whom it may concern:

Be it known that I, ROBERT S. WEST, a citizen of the United States, residing at Cleveland, in the county of Cuyahoga and State of Ohio, have invented certain new and useful Improvements in Disinfecting Apparatus, of which the following, with the accompanying drawings, is a specification.

This invention relates to certain new and useful improvements in disinfecting apparatus.

The invention has for its object the construction of a device which shall be cheap and simple in point of construction and that shall 15 specially be adapted for delivering a liquid disinfectant automatically in greater or less quantity, as may be desired.

To this end the invention consists in the novel features and combinations of the several parts, all as more fully hereinafter set forth, and pointed out in the claim.

Figure 1 is a side elevation of my improved device. Fig. 2 is a similar view, partially in section and at right angles to Fig. 1. Fig. 25 3 is an enlarged elevation of the conductor-tube and its conductor detached.

A represents a sheet-metal case or receptacle provided with any suitable means by which it may be secured to the wall or other 30 support. This case or receptacle is open at the top, and it is provided with the inwardly-projecting ribs or lugs b, upon which the tank B is designed to rest when in place. This tank B is provided with a removable neck C.

35 D represents a conductor-tube which projects through the bottom of the receptacle A, and E is an adjustable conductor. This conductor I preferably form by weaving or braiding a horsehair covering upon a copper or 40 other wire which is bent into substantially the form shown. The longer and straight arm of this conductor is placed within the conductor-tube and is designed to reach nearly to the bottom thereof, while the bent 45 portion is intended to clasp the tube, so that the conductor may be readily adjusted vertically thereupon and for the purpose herein-after described.

The operation of the device is as follows: 50 The receptacle A is secured to a suitable sup-

port and so that its conductor-tube D will be over the spot where the disinfectant is to be delivered. After the tank has been filled with the disinfecting liquid it is inverted and placed within the case A, resting upon the ribs 55 b, thus allowing the liquid to flow into the case A until it rises high enough therein to "seal itself" around the neck and submerge the outer portion of the conductor E. The liquid will climb up the exterior of the conductor, pass down through the tube D, and escape therefrom drop by drop, more or less frequently, as may be determined by the vertical adjustment of the conductor. It will readily be understood that the higher the conductor above the surface of the liquid the 60 slower must be the delivery, and when lowered such delivery will be faster. The conductor can be readily adjusted by inserting a pencil or stick in one of the openings c and 65 pushing the conductor up or down, as may be required.

It will be observed that the conductor does not extend to the bottom of the case A, but is just below the surface of the liquid. In 75 this position it draws the liquid from near the top above the sediment which may accumulate at the bottom of the case, and as the liquid travels up and over the surface of the conductor instead of through it, as is the case 80 where a fabric wick is employed, the conductor remains clean and does not easily become fouled.

What I claim as my invention is—

The combination in a disinfecting apparatus of an outer case A, provided with a conductor-tube projecting through its bottom, an inverted receptacle B, within said case, and provided with a removable neck C, the outlet of which is below the plane of the inner end of said tube D, and an adjustable conductor E, the parts being constructed, arranged and operating substantially in the manner and for the purpose set forth.

In testimony whereof I affix my signature 95 in the presence of two witnesses.

ROBERT S. WEST.
